To all whom it may concern:

Be it known that I, Edwin Pugsley, a citizen of the United States, residing at New Haven, in the county of New Haven and State of Connecticut, have invented a new, original, and ornamental Design for a Firearm, of which the following is a specification, reference being had to the accompanying drawings, forming part thereof.

The characteristic features of my design reside in the portions of the firearm illustrated on an enlarged scale in Figs. 2 and 3.
